EP	2 549 030	1/2013
WO	WO201302326	2/2013

Primary Examiner — Keli L Hill*Assistant Examiner* — Harold E Blackwell, II(74) *Attorney, Agent, or Firm* — Kirk A. Buhler; Buhler & Associates Patenting(57) **CLAIM**

The ornamental design for a tile leveler, as shown and described.

DESCRIPTION

FIG. 1 is a top perspective view of a tile leveler, showing my new design;

FIG. 2 is a left side elevation view, the right-side elevation view being a mirror image thereof;

FIG. 3 is a front elevation view, the rear elevation view being a mirror image thereof;

FIG. 4 is a top plan view thereof;

FIG. 5 is a bottom view thereof;

FIG. 6 is a left side sectional view taken along lines 6-6 from FIG. 5 thereof;

FIG. 7 is a rear sectional view taken along lines 7-7 from FIG. 5 thereof;

FIG. 8 is a bottom perspective view thereof;

FIG. 9 is an exploded top perspective view; and,

FIG. 10 is a top perspective view shown in an environment of use.

The broken lines in FIGS. 1-10 depict environmental subject matter and form no part of the claimed design.

1 Claim, 7 Drawing Sheets(56)
